PAPER HOLDER

Francis Eugene Sloan, Baltimore, Md.

Application August 23, 1937, Serial No. 160,371

3 Claims. (Cl. 88—24)

This invention relates to a paper holder for use primarily in making photographic enlargements.

In making enlargements from relatively large 5 negatives, the enlarging light and the part of the negative which it is desired to block out can fairly readily be masked from the positive, but in enlarging from the negative of the smaller cameras that are now so popular, it is very difficult to hold the small negative in place and still 10 get the positive printed in the exact place on the paper that may be desired and to protect the rest of the paper from the light.

For enlargements from such small negatives, 15 it is desirable to locate the positive in a particular position on the paper and frequently a wide margin or border is desired. With devices now in use certain fixed borders may be obtained, but with the device of this invention, very large, and 20 very narrow borders may be obtained as well as borders of any intermediate width. After once setting the device to obtain the desired border, successive prints may be made in the dark room without disturbing the border arrangement and 25 with the positive assurance that each picture will have the identical position on the paper that is desired. The sensitive emulsion on photographic paper used for enlarging is on the upper side, and consequently the paper curls upwardly at 30 the edges. In this invention stops are provided which bear up against the mask, under which the paper is inserted, so the upper curling edge will always be engaged by these stops. These stops may be moved to several different positions to 35 give different border widths. The stops are placed a fixed distance apart and for borders of widths between the stops, adjustments of the mask in the two positions at right angles to each other are provided.

40 Other objects and advantages of the invention will appear from the following description and accompanying drawing in which similar numerals refer to similar parts in the views.

Figure 1 is a plan view of a holder embodying 45 the invention.

Figure 2 is a partial sectional view of the holder on line 2—2 of Figure 1.

The base 1 has therein holes 2, the two separate groups of which are in lines, in one group 50 parallel to the back of the base and in the other to the sides of the base. The lines of holes are a fixed distance apart. Pins 3, having in their centers springs 4, which urge the pins upwardly, may be placed in any two holes in a line parallel 55 to the back of the base and two more in holes

in a line parallel to the side, and when a piece of printing paper 5 is placed against these four pins, it will be square in respect to the sides of the base.

A mask 6 having edges 7 and 8 at right angles 5 to each other and parallel to the lines of the pin holes is placed on the paper 5, both to hold the paper down on the base, and to cover the edge of the paper to prevent the light from striking it, in order to form a margin on the picture 10 being printed. This mask is hinged at 9 and 10 to a plate 11, on the lower side of which are two racks 12. An elongated pinion 13, in brackets 14, having thumbheads 15 thereon engage the two racks, and by which they may be moved back 15 and forth. The base is cut out as at 16 to give room for the movement of the racks and hinges and yet allow the mask to lie flat on the base. The cut out portions 16, at 17 have edges forming 20 stops to limit the forward movement of the hinges, and therefore of the mask. The mask has thereon a hold member 18 projecting from its side, by means of which it may be moved sidewise, the racks keeping their position with respect to the back of the base, but the elongated pinion allowing them to slide thereover. The openings 19 are large enough to allow this 25 movement, and their sides form proper stops to limit the sidewise movement of the mask. Graduations 19 are on edges 7 and 8 of the mask. 30

The pins 3 are urged upwardly against the under side of the mask so that, though the paper 5 curls upwardly, the pins form positive stops for it.

After locating the paper on the base, and setting the mask 6 for two sides of the paper, the masks 20 and 21 are moved to the desired positions as determined by the graduations 19 to mask the other two edges of the paper. The base 1 has brackets 22 thereon in which is pivotally mounted the square rod frame 23. This frame has on its rear and left side depending members 24, the inner edges 25 of which project downwardly and securely hold mask 6 down during a printing operation. Also on the rear and 45 left side of the frame are resiliently held carriages 26 to which the masks 20 and 21 are attached. These carriages 26 have knobs 27 by which they are movable along the rods of frame 23. Arc 28, striking bar 29, limits the upward 50 and backward swing of the frame 23.

When it is desired to make a print, the exact location for the picture on the paper may be determined by placing a pair of L squares on the paper and moving them around until this exact 55

location is found. Then the paper is placed on the base 1 and pins 3 are put in the locations nearest to the desired margins, and the paper placed against the pins. The mask 8 is then lowered, and moved back or forth and sidewise, until the exact desired picture location and margin are obtained. Then masks 20 and 21 are moved to complete the margins on the other two edges. With this setting, any number of prints 10 may be made by simply raising the masks and removing and inserting successive sheets, without disturbing the location of the masks, and these operations may be carried on in the dark room, without additional light.

15 While the invention has been described as a paper holder for use in making photographic enlargements, it may be used for holding paper for other purposes.

Having thus described the invention, what is 20 claimed as new and is desired to be secured by Letters Patent is:

1. In a holder for paper, the combination with a base, pinions along one edge thereof, rack bars engaging said pinions and a mask hinged to said 25 rack bars, means projecting from said base against which to position paper thereon and under said mask, said mask being movable by said racks and pinions in a straight line over

said base to vary the margin of the paper thereunder.

2. In a holder for paper, the combination with a base, elongated pinions along one edge thereof, rack bars engaging said pinions and a mask 5 hinged to said rack bars, means projecting from said base against which to position paper thereon and under said mask, said mask being movable by said racks and pinions in a straight line, and said racks being slideable along said pinions 10 in a direction at right angles to said straight line, to vary the margin of the paper thereunder.

3. In a holder for paper, the combination with a base, elongated pinions along one edge thereof, rack bars engaging said pinions and a mask 15 hinged to said rack bars, said base having therein a plurality of openings, resiliently projecting pins in a selected group of said openings contacting the under side of said mask and serving as guides against which to position paper upon said 20 base and under said mask, said mask being movable by said racks and pinions in a straight line, and said racks being slideable along said pinions in a direction at right angles to said straight line, to vary the margin of the paper thereunder 25 for any amount not allowed by the possible positioning of said pins.

FRANCIS EUGENE SLOAN.
